ATTACHABLE CONTAINER BRACKET FOR LADDERS

Clifford John Glasgow, 6318 Hickman Ave.,
Des Moines, Iowa

Filed Feb. 18, 1958, Ser. No. 715,876

2 Claims. (Cl. 248—210)

This invention relates to containers and more particularly to a container that may be easily attached to or detached from a ladder for holding paint, brushes, supplies, tools or like.

One of the most difficult tasks is to balance one's self on a ladder, hold a can of paint in one hand, and the brush in the other hand during the painting operation. Also, the paint can is usually of a gallon capacity and, due to its weight, is quite tiresome to hold over an extended period of time. Furthermore, the paint being so held is often spilled. Many tasks performed on a ladder are just as much of a problem as that of painting.

Therefore, one of the principal objects of my invention is to provide a detachable bracket for ladders that will successfully hold a container such as a paint can.

A further object of this invention is to provide a container bracket for ladders that will fit ladders having both flat steps and shaft steps round in cross section.

A still further object of this invention is to provide a container bracket that rigidly locks the container into the bracket against accidental detachment therefrom.

A still further object of this invention is to provide a container bracket for ladders that is light weight.

Still further objects of my invention are to provide a container bracket for ladders that is economical in manufacture, durable in use, and refined in appearance.

These and other objects will be apparent to those skilled in the art.

My invention consists in the construction, arrangements, and combination, of the various parts of the device, whereby the objects contemplated are attained as hereinafter more fully set forth, specifically pointed out in my claims, and illustrated in the accompanying drawings, in which:

Fig. 1 is a perspective view of my device mounted on a ladder having round rungs;

Fig. 2 is a perspective view of my container bracket mounted on a ladder of the flat step type;

Fig. 3 is an enlarged side view of my bracket and more fully illustrates its construction;

Fig. 4 is an enlarged end view of the device and is taken from line 4—4 of Fig. 3; and

Fig. 5 is a top plan view of my container bracket disassembled and folded for shipment or storage.

In these drawings, I have used the numeral 10 to designate the ring portion of the device formed by bending a circle in the central area of a metal strap. The two free ends of the strap extend radially from the ring 10, as shown in Fig. 5, and these two end portions 11 and 12 are secured together by bolts, rivets, or like 13. If desired, these two end portions may be welded together. One rivet also secures to these end projections a horizontal U-member 14. The inner length of the member 14 is secured at its end to the ring 10, as shown in Fig. 1. This U-member 14 is adjacent the ring 10 and is preferably of spring material. The numeral 15 designates a horizontal slot extending through the ends 11 and 12 near their outer ends. The numeral 16 designates a

2

wing nut bolt extending through the slot 15. This bolt 16 extends through the center of a two-hook member 17. Each end of this member 17 is in the form of a curved hook and it is held in a vertical position by having its center area bent into a rectangular portion around the two end portions 11 and 12. Due to the slot 15 the hook member 17 may be adjusted different distances from the ring 10. The numeral 18 designates a U-member having its two ends riveted and hinged to the ring 10 at diametric opposite sides of the ring, as shown in Fig. 5. The numeral 20 designates a curved clamp member of spring material riveted and hinged at its center to the ring 10 at a point between the two points where the member 18 is pivoted to the ring 10. The two outer free ends of the member 20 are curved inwardly toward the ring 10. The numeral 21 designates a container adapted to be slid downwardly into the ring 10 until it rests in and on the U-member 18. By rotating the clamp cam member 20 from a horizontal position to a vertical position, it will yieldingly engage the container 21, thereby securing my bracket rigidly to the container.

As herebefore indicated, my container bracket may be easily and quickly attached to or detached from almost any type of ladder. Fig. 1 illustrates a ladder having round type rungs 22 and the usual two vertical side standards 23 and 24. To attach my device to such a ladder, the hook member is hooked over one of the rungs 22, as shown in Fig. 1. With the wing nut loosened, the hook member and ring are slid towards each other to bring the hook member adjacent the inside of the standard 23, and the ring and container adjacent the outer side of the standard 23. The wing nut is then tightened and the bracket will support the container in a rigid upright condition. The slot 15 will compensate for standards of different widths. If it is desired to place the bracket on the other side of the ladder, i.e., to the standard 24, the same procedure is used, except the hook member is turned over and the other hook end used over the rung. To remove the container and its bracket, it is merely necessary to lift the unit upwardly until the hook member is clear of the round rung.

In Fig. 2 I show a ladder having flat steps 25 and side vertical standards 26 and 27. To place my device on such a ladder, it is merely necessary to horizontally slide the U-member 14 onto the standard 27 just above a step 25. The step prevents the downward sliding of the unit and supports the container. If the unit is to be placed at the other side of the ladder, i.e., to the standard 26, the entire unit (with the container removed) is turned over and the U-member 18 swung to a lowered position. Thus, it will be appreciated my bracket will successfully fit both types of ladders.

For purposes of shipment or storage, the hook member is removed and placed inside the ring 10 and the U-member 18 and cam lock 20 moved to horizontal positions, as shown in Fig. 5. When the device is so positioned and conditioned, it provides a very flat package. While I have described my device as made of metal, it can also be made of other suitable materials such as plastics.

60 Some changes may be made in the construction and arrangement of my attachable container bracket for ladders without departing from the real spirit and purpose of my invention, and it is my intention to cover by my claims, any modified forms of structure or use of mechanical equivalents which may be reasonably included within their scope.

I claim:

65 1. In a container bracket, a ring portion, a U-shaped saddle member having its two ends secured to said ring portion, a means for securing a container in said ring and on said U-shaped saddle member, a radially extend-

ing projection on said ring, and a vertical hook member horizontally slidable on said projection.

2. In a container bracket, a ring portion, a U-shaped saddle member having its two ends secured to said ring portion, a means for securing a container in said ring and on said U-shaped saddle member, a radially extending projection on said ring, a vertical hook member on said projection and a horizontal U-shaped member extending from said projection.
